UNITED STATES PATENT OFFICE.

FREDERICK S. GLINES, OF LYNN, MASSACHUSETTS, ASSIGNOR TO LORENZ MUTHER,
OF NEWTON, MASSACHUSETTS.

SLITTING DEVICE FOR FOLDING MACHINES.

Application filed September 11, 1922. Serial No. 587,267.

This invention relates to a slitting device for use on folding and similar machines, and more particularly to such a device adapted to be manually operated independently of the operation of the machine, and is designed with special reference to that class of folding machines used in binding the edge of flexible material with what is commonly known as "French" or cord binding.

In the use of folding machines for applying "French" or cord binding such, for instance, as that shown in an application filed by me jointly with Lorenz Muther July 24, 1922, Serial No. 576,965, it is necessary to slit the binding tape at one or more points when going around concave curves, in order that the tape may be applied smoothly without curling or stretching at the edge. It is impracticable to use for this purpose the automatic form of slitting device common to folding machines, since when such device is thrown into operation, it acts with such rapidity that it is apt to make a plurality of cuts before it can be thrown out of operation, which cuts interfere with securing a clean folded edge in cord binding work and break up the continuity of the folded edge. Heretofore, it has generally been customary for the machine operator to slit the tape at the necessary point or points with a pair of scissors, which necessarily slows up the operation of the machine, and may result in slits which are either too long or too short.

The main object of the invention is the provision on a machine of the character described of a simple and efficient slitting device, adapted to be manually operated at any time by the operator without interfering with the operation of the machine.

Another object of the invention is the provision of a slitting device which does not obstruct or interfere with the handling of the work during the operation of the machine, and which is visible to the operator and so placed that the operator can easily adjust the work in relation thereto in order to determine the location, depth and angle of the slit.

Other objects of the invention will be more specifically set forth and described hereinafter.

My invention contemplates in its preferred form the provision of a block, having

a shearing edge, set in the work-support of the machine, a movable knife-blade co-operating therewith, said knife-blade being normally below the surface of the work-support, together with means for operating the movable knife-blade either with the foot or hand whenever desired, so that the knife-blade is raised above the work-support and then released to cut the edge of the tape or other material.

In the drawings illustrating my invention, Fig. 1 is a side elevation of the end portion of a folding machine of the character shown in the Muther-Glines application hereinbefore referred to, having a slitting device constructed and operated in accordance with my invention applied thereto. Fig. 2 is a plan view of the work-plate and mechanism mounted thereon. Fig. 3 is a longitudinal, vertical, sectional view on line 3—3 in Fig. 2, showing the movable knife in raised position, preparatory to slitting. Fig. 4 is a similar view, showing the movable knife in normal position. Fig. 5 is a transverse, sectional view on line 5—5 in Fig. 1. Fig. 6 is a portion of material having a concave curve, with the binding tape turned over on a portion of the curved edge and provided with a slit, illustrating the location and angle thereof.

In the drawings is shown one form of slitting device embodying my invention applied to a folding machine of the type illustrated in said joint application hereinbefore mentioned, to which reference may be made for a more particular description of the construction and mode of operation of the folding machine itself. For convenience, the reference numerals employed in said application have been retained for such parts of the folding machine as are shown herein to illustrate the application of my novel slitting device.

Referring to the drawings, 15 indicates the lower arm and 16 the upper arm of the frame of the machine, 20 a feed-bar, 21 an idler roll, 22 a housing in which the feed-bar is slidably mounted, and 24 a feed-foot formed on the lower extremity of the feed-bar, which co-operates with the idler roll for feeding the material forward in a step-by-step manner. 26 designates a link and 27 a stud carried by a split collar 28, constituting a part of the means for reciprocating the feed-bar 20 in the housing 22 at the neces-

sary times during the feeding movement. The idler roll 21 is loosely mounted on a screw stud 32 set in the end of the lower arm 15.

- 5 A guide-bar 35 with a guiding edge 36 is slidably mounted in bearings 37 and 38, integral with a bracket 39 secured to the upper arm 16 in such position that the guide-bar is held in a depending position over the 10 work; the guiding edge being adapted to engage the edge of the material above the tape or binding material. A split block 40 is adjustably mounted on the guide-bar 35 and secured thereto in an adjusted position by a 15 screw 41, and a helical spring 43 mounted on the guide-bar 35 between the upper bearing 37 and the split block 40 holds the guide-bar in a downward position, with the split block 40 in engagement with the lower bearing 38. 20 This block is provided with a handle 44 for raising the guide-bar 35 out of operative position, and the bracket 39 has a recess (not shown) to receive the end 47 of the split block to permit the guide-bar to be turned 25 and locked in inoperative position.

A work-support 50 is mounted upon the end of the lower arm 15, and on the side toward the operator is secured a thin, stationary plate 53 having a turned-up, slightly 30 hooked-over, thin edge lying oblique to the normal line of feed for wiping over the tape or binding to straighten it as it is fed forward, preparatory to the turning operation. A plow or turner 58 turns the tape over and 35 around the edge of the material, and a presser 62 presses the tape down upon the reverse side of the material to be bound. All of the foregoing construction is fully shown and described in the joint application herein- 40 before referred to.

The novel features of my invention reside in the slitting device, one embodiment of which is shown in the drawings, comprising a block 100 having a shearing edge 101 and a knife-blade 102 provided with a shearing edge 103 to co-operate with the said block. The former member is secured within a recess in the work-support 50 in front of the plow 58 by a screw 105; the upper face of the block 100 being approximately in the same plane as the upper face of the work-support 50. The knife-blade 102 is secured by a hexagonally headed screw 106 to a bar or lever 107; the knife-blade being provided 55 with a slot 108 which permits it to be adjusted along the bar or lever 107. The latter member is in turn pivotally mounted on a shaft 110, set transversely in side webs 111 and 112 of the lower arm 15; this arm being 60 adapted to be rocked on the shaft 110 for raising and lowering the knife to perform the cutting or slitting operation.

Preferably, means are provided for operating the knife either by the hand or the 65 foot of the operator, and these means may

be of any suitable forms. For operating it by a treadle, the free end of the arm 107 is bored and threaded to receive a screw 114, held in an adjustable position by set nut 115 and having a head 116 formed to receive a 70 chain 117 which may be connected to a treadle not shown. The upper end of the screw 114 engages the underside of the work-support 50, and the upward throw of the arm 107 may be adjusted by turning the 75 screw 114 in one direction or the other in the arm 107, the set nut 115 serving to hold it in that position.

For operating the arm 107 by hand, a lever 120 and a flat finger piece 121 may be 80 secured to the lever by screw 122. The lever is bent downwardly under the side web 112 and then upwardly, so that the finger piece 121 is a short distance below the work-support and toward the operator where it may 85 be easily reached during the operation of the machine.

For holding the knife-blade in a downward or normal position as shown in Fig. 4, any suitable means may be provided such 90 as the helical spring 125 coiled about the shaft 110, having one end 126 held under the end portion 127 of the lower arm 15 of the machine and the other end 128 held under the screw 122; this spring being under 95 tension at all times.

The operation of my device is extremely simple. The knife-blade is normally held in its lowermost position by the spring 125, the blade being provided with an angular recess 130 which engages the web 127. In this position the upper edge of the knife-blade is approximately in, or slightly below, the plane of the upper face of the work-support 50. The shearing edges of the knife-blade 102 and the block 100 are substantially 100 perpendicular to the normal line of feed of the material through the machine, although it may be set at an oblique angle, if desired. The slitting device may be operated at any 110 time by rocking the lever 107 on the shaft 110, either by means of the foot treadle or the finger piece 121, which raises the knife-blade, and then releasing the same, whereupon the spring 125 returns the knife-blade 115 to its normal position, effecting the slitting operation. The knife-blade is, as a rule, 120 under the material, and as it is raised it raises the edge of the material or the tape, freeing itself therefrom, allowing the tape 125 to fall back upon the work-support, and then cutting the tape as it is thrown downwardly by the spring. The device is entirely independent of the operation of the machine, and may be used during the operation of the machine or when it is not in operation.

When my slitting device is used on machines of the character herein shown and described, it is of course necessary to cut 130

the tape or binding material only on concave curves, since the straight portion of the tape lies normally unstretched and on convex curves is formed naturally into pleats by the pressing operation. It is important in a machine of this character that the slit should be oblique to the edge of the material being bound, and in Fig. 6 I have shown a piece of material 132 with tape 133 attached to the edge thereof, and partially turned over and folded on the portion 134, and unfolded on the portion designated by 135. The edge of the material 132 to be bound is cut on a concave curve, calling for a slit in order that the tape may be pressed down on the reverse surface. In performing this work on material 132, it would be presented to the machine as shown in Fig. 2 in the same relative position that it is shown in Fig. 6, so that the slitting, although accomplished by a knife which is perpendicular to the line of feed, will still be oblique to the edge of the material as shown in Fig. 6; it being observed that the slit in Fig. 6 is substantially parallel with the knife in Fig. 2. The depth of the cut may of course be regulated by the operator in adjusting the material, just before it is slit, in relation to the knife.

The cutting of the slit obliquely, as shown in Fig. 6, is an important feature, because if the cut were perpendicular to the edge of the material or oblique in the reverse direction, there would be a liability of the sharp point of the portion 133 of the tape catching on the plow and wrinkling up, forming a bunch or defective binding at that point. With the slit turned as shown, it slides by the plow without catching.

What I claim is:

1. In a folding machine, the combination with a work-support and folding instrumentalities of two cooperating shearing members mounted at a right angle to the normal line of feed and below the surface of said work-support, resilient means for holding said shearing members in normally closed position and manually operated means for opening said shearing members against the tension of said resilient means into a slitting position.

2. In a folding machine, the combination with a work-support and folding instrumentalities of two cooperating shearing members mounted below said work-support, resilient means for holding said members in normally closed position and manually operated means for opening said members against the tension of said resilient means.

3. In a folding machine, the combination with a work-support and folding instrumentalities of two co-operating shearing members mounted below said work-support, a spring for holding said members in a normally closed position and manually operated

means for opening said members against the tension of said spring to accomplish the cutting action when said manually operated means are released.

4. In a folding machine, the combination, with folding instrumentalities of manually operated means for slitting the edge to be folded; said means being mounted below the surface of the work support and underneath the edge of the material with its slitting edges transverse to the normal line of feed.

5. In a folding machine, the combination, with folding instrumentalities, of means for slitting the edge to be folded; said means being mounted below the surface of the work support with its slitting edges perpendicular to the normal line of feed.

6. In a folding machine, the combination, with folding instrumentalities, of means for slitting the edge to be folded; said means comprising a shearing block set in the work support, a movable knife plate mounted below the work support and normally in an inoperative position, the slitting edges of said block and said knife plate being transverse to the normal line of feed, and means for operating said knife plate.

7. In a folding machine, the combination, with a work-support, of a slitting device comprising a fixed shearing member and a movable shearing member, both of said members being mounted below the top surface of said work-support with their shearing edges perpendicular to the normal line of feed, and manually-operated means for operating said movable member independently of the operation of the machine, for cutting a slit in the edge of the material being operated upon.

8. In a folding machine, the combination, with a work support of a slitting device, two shearing members, one fixed and the other movable, both of said members being mounted below the surface of said support with their shearing edges transverse to the normal line of feed, and manually operated means for operating said movable member.

9. In a folding machine, the combination with a work support of instrumentalities for folding a binding around the edge of a sheet of material, of two co-operating slitting members, one fixed and the other movable, and both mounted below the top surface of said work support with slitting edges transverse to the normal line of feed and manually operated means for operating said movable member to slit.

10. In a folding machine, the combination, with a work-support and instrumentalities for folding a binding around the edge of other material, of two co-operating slitting members, one fixed and the other movable and both mounted below the top surface of said work-support, a lever pivotally mounted and carrying said movable member, a

- spring for holding said lever in an inoperative position, and manually-operated means for moving said lever to cutting position against the tension of said spring.
- 5 11. In a folding machine, the combination, with a work-support and folding instrumentalities, of two co-operating shearing members mounted below the top surface of said work-support, a spring for holding said members normally in closed position, and manually-operated means for opening said members against the tension of said spring.
- 10 12. In a folding machine, the combina-

tion, with a work-support and folding instrumentalities, of two co-operating shearing members mounted below the top surface of said work-support, one of said members being adjustable in relation to the other, a spring for holding said members normally 15 in closed position, and manually-operated means for opening said members; said spring serving to close said members for slitting when said manually-operated means is released.

In witness whereof, I hereunto set my hand this sixth day of September, 1922.

FREDERICK S. GLINES.
